HAIR WAVING APPARATUS

Peter Santurello, Columbus, Ohio

Application March 20, 1935, Serial No. 12,040

20 Claims. (Cl. 132—33)

My invention relates to hair-waving apparatus. It has to do, more particularly, with that type of hair waving apparatus which is used for producing what is commonly known as a Croquinole wave in the hair.

One of the objects of my invention is to provide hair-waving apparatus of the type indicated which embodies a novel type of hair clamping and protecting member and a mandrel mounted thereon in a desirable manner.

Another object of my invention is to provide a hair clamping member which is of such a nature that it will grip the hair firmly regardless of the thickness of the strand inserted therein so that there will be no danger of slippage of the hair through the clamping member or passage of steam or hot waving fluid therethrough.

Another object of my invention is to provide a hair clamping member which may be readily applied to the hair and which may be easily and quickly operated to firmly grip the hair.

Another object of my invention is to provide a hair clamping member of such a nature that it will not injure the hair to which it is applied.

Another object of my invention is to provide a device for waving hair which embodies a hair clamping member and a mandrel which is carried thereon in such a manner that it may be removed from the clamping member after the hair has been wound and tightened thereon, without first removing the clamping member from the strand of hair.

In its preferred form my invention comprises a clamping member which includes two arms that are pivoted at one end so that they may be swung apart for insertion of the hair and then may be swung together to grip the hair. I provide a wedge lock on the clamping member which is operable from one end of the device and which will cause the clamping member to firmly grip the strand of hair regardless of the thickness thereof. This clamping member preferably carries, the mandrel is preferably mounted in such a manner that it may be rotated in one direction to tighten the hair thereon but rotation in an opposite direction will be precluded. Furthermore, the mandrel is preferably mounted in such a manner that it may be removed from the clamping member without first releasing the hair from the clamping member.

The preferred embodiment of my invention is illustrated in the accompanying drawings wherein similar characters of reference designate corresponding parts and wherein:

Figure 1 is a perspective view, partly broken

away, of a hair clamping member made in accordance with my invention and showing the arms thereof spread apart to receive a strand of hair.

Figure 2 is a longitudinal section of the structure illustrated in Figure 1 showing the two arm members brought together but before the wedge lock is operated to bring such members into firm contact with each other.

Figure 3 is a transverse section taken substantially on line 3—3 of Figure 2.

Figure 4 is a perspective view of my hair-waving apparatus illustrating the clamping member with the mandrel mounted thereon and with hair wound and tightened on the mandrel.

Figure 5 is a side elevation, partly cut away, of the hair-waving apparatus.

Figure 6 is a longitudinal section of a slightly modified type of locking mechanism for holding the two arm members in clamping relation to the hair.

Figure 7 is a longitudinal section of a slightly different type of locking mechanism for holding the two arm members in clamping relation to the hair.

With reference to the drawings and particularly to Figures 1, 2, and 3, I have illustrated the hair clamping member of my apparatus as comprising mainly a pair of arm members which are designated 1 and 2 and which are pivotally secured together adjacent one end as at 3. Thus, they may be swung apart as indicated in Figure 1 for the reception of a strand of hair or may be swung together as indicated in Figure 2 so that they may be caused to firmly grip the hair.

Each arm member preferably comprises a metal member 4 which preferably has a strip 5 of wood or other suitable material which will not readily conduct heat fastened to the lower surface thereof. This strip of wood 5 is provided with cutouts 6 which will permit circulation of air between the wood strip and the metal member 4. To the lower surface of each wood strip 5 is preferably secured a strip 7 of felt or other soft material. Thus, the scalp of the person on which this device is placed will be fully protected from heat.

Each of the members 4 is substantially hollow. The outer edge of each of the members is closed as at 8. The inner edge is open but a longitudinally extending wall 9 is provided at a point spaced from the inner edge of each of these members. Thus, a socket is provided at the inner edge of each of the members 4 for receiving a block 10 of rubber or other suitable material

for gripping the hair without injury thereto. Each block of rubber is merely slipped in the socket which receives it and may be readily removed when it becomes warm. The block of 5 rubber is provided with flanges at its outer edge which extend over the edges of the bottom and top plates of the member 4 as indicated in Figure 1. The outer surface of each of these blocks is roughened as at 10' so there will be no danger of 10 slippage of the hair. It will be apparent that a longitudinally extending chamber 11 is formed in each of the members 4.

The arm members 1 and 2 are normally held apart as indicated in Figure 1 by a grasshopper 15 spring 12 which is shown best in Figure 2. This spring is mounted on the pivot pin that pivotally connects the arms 1 and 2 together. One of the free ends of the spring bears against the wall 9 of the member 4 of one of the arms while the 20 other free end of the spring bears against the wall 9 of the member 4 of the other arm. The free ends of the spring normally tend to spread apart and, consequently, the spring will normally tend to keep the arm members 1 and 2 spread apart.

25 In order to maintain the arm members 1 and 2 together, when desired, for gripping a strand of hair therebetween I provide the structure to be described now in detail. As shown, a wedge member 13 is mounted for longitudinal sliding movement in the chamber 11 formed in the arm 1. This member 13 has a narrow portion 14 formed at one end having a plurality of rack teeth 15 formed on its lower edge. Beneath this portion 14 the inner end of a pin 16 is disposed and has 30 a worm or screw 17 formed thereon. As shown, this worm will engage the teeth 15 on the lower edge of the portion 14 of the wedge member 13. The pin 16 has its outer end rotatably mounted in a bearing member 18 and it extends from this 35 bearing member a sufficient distance to have a knurled knob 19 keyed on its outer end. It will be apparent that rotation of knob 19 will cause longitudinal movement of the wedge member 13. Since the mechanism for causing the longitudinal 40 movement of the wedge member comprises screw and rack mechanism, it will be understood that the wedge member will be firmly locked in any 45 position to which it is moved.

The opposite end of the wedge member 13 is 50 inclined as at 20. This inclined portion extends for a considerable length of the wedge member. This extreme end of the wedge member is curled upwardly as at 21. This curled portion receives the laterally extending portion 22a formed on the 55 inner end of a latch member 22. This latch member extends through a space 23 in the arm member 1 and projects inwardly from this arm member. When the two arm members are swung together, the outer end of this latch member projects into a space 24 formed in the arm member 2. The latch member is provided with a lug 25 on its outer end which will pass beneath a keeper 26 disposed at one side of the space 24 in the arm 2. A flat spring 27 is provided for causing 60 the lug 25 on the latch 22 to pass beneath the keeper 26. It will be apparent that this spring 27 is so inclined that when the arms 1 and 2 are swung together, it will engage the outer end of the latch 22 and force the lug 25 thereof beneath the keeper 26. The inner end of the latch 22 has a tension spring 28 connected thereto and the opposite end of this spring is connected to the arm member 1 as at 29. This spring normally urges the outer end of the latch 22 towards the 65 right (Figure 2).

In using this clamping device assuming that the arms are in the position indicated in Figure 1, the hair is slipped therebetween. Then the arms are swung together against the action of the spring 12 until the latch member 22 engages the 5 spring 27 which will force the outer end thereof to the right until the lug 25 will lie beneath the keeper 26. The two arm members and the wedge member 13 will, at this time, be in the positions indicated in Figure 2. Then if the knob 19 is 10 rotated in the proper direction, the wedge member 13 will be moved toward the left. This will cause the portion 22a of the latch member 22 to ride up on the inclined surface 20 of the wedge member. Since the latch member will always be 15 held in firm engagement with the keeper by the spring 27, this will cause the two arm members to be drawn firmly into contact with each other. Regardless of the thickness of the strand of hair being gripped between the members 10, the hair 20 will be firmly gripped and there will be no danger of slippage. The final position of the portion 22a of the latch member along the inclined surface 20 will depend on the thickness of the strand of hair being gripped. However, it will be apparent 25 that the hair will be gripped with gradually increasing intensity as the wedge member 13 is moved longitudinally.

To release the hair, it is merely necessary to rotate the knob 19 in the opposite direction. 30 This will move the wedge member 13 to the right and will permit the portion 22a of the latch to slide down along the surface 20 until it occupies the position indicated in Figure 2 where it is disposed in the curled portion 21 of the wedge 35 member. At this time the right hand edge of the latch 22 will be in engagement with the side of the space 23 and if movement of the wedge member 13 to the right is continued, the curl 21 will engage the portion 22a, pulling the inner end 40 of the latch 22 to the right and forcing the outer end of the latch to the left against the force of the spring 27 until the lug 25 is out of engagement with the keeper 26. At this time, the two arm members will automatically spread apart 45 because of the action of the spring 12.

The spring 28 will urge the outer end of the latch member 22 to the right as previously stated and, consequently, when the arm members are again swung into cooperative relation the latch 50 member will automatically engage the keeper without operating the wedge locking mechanism. However, the wedge locking mechanism may then be operated to lock the two arm members in firm gripping relation to the hair disposed therebetween. The hair will be positively locked in the clamping device until the knob 19 is again 55 rotated to release it.

The hair clamping and protecting member just described is adapted to carry a mandrel which 60 may be mounted thereon in a suitable way. I preferably mount the mandrel on the clamping member in a manner to be described now.

The mandrel 30 as shown best in Figures 4 and 5 comprises a body portion which is rotatably 65 mounted on an extension 31 at one end thereof. This extension 31 is connected to the mandrel through the medium of a spring clutch 32. This clutch 32 permits rotation of the body portion of the mandrel relative to the extension 31 in one 70 direction but precludes relative rotation thereof in an opposite direction. The extension 31 is provided with slots 33 arranged at right angles to each other. A latch member 34 is pivoted to the arm member 2 of the clamping member adjacent 75

one end thereof as at 35. This latch member may be swung into or out of the slot 33 in the extension 31 of the mandrel. When the latch 34 is in the slot 33 rotation of the extension 31 in either direction is precluded. The opposite end of the arm 2 of the clamp is provided with a yoke 36 which cooperates with a circumferential slot 37 formed in one end of the mandrel in order to prevent longitudinal movement of the mandrel relative to the hair clamping member. The latch member 34 may be swung down into a space 38 between the two arm members of the clamping member when the mandrel is not disposed thereon.

15 The mandrel 30 is provided with a member 39 which is pivoted thereto as at 40 for swinging relative to the mandrel. This member is adapted to grip the free end of the strand of hair to the mandrel when in operative position as indicated 20 in Figure 5 where it embraces the mandrel. A removable key 41 is provided with a square portion 42 which may be inserted in a socket in the end of the mandrel. This portion 42 is of such a length that when it is inserted in said socket rotation of the key 41 will not be interfered with by the knob 19, as indicated in Figure 5. By means of this key, the body portion of the mandrel may be rotated relative to the extension 31.

In using this hair waving apparatus, the 30 clamping member is applied to the hair as indicated and will firmly grip it. The free end of the hair is placed beneath the member 39 and this member is held down against the mandrel so that the free end of the hair will be clamped thereto. The hair is then wound on the mandrel and the mandrel simultaneously moved down towards the clamping member. When the clamping member is reached the end of the mandrel is inserted in the yoke 36 and the latch 34 is swung 40 into the slot at the opposite end of the mandrel. Then the key 41 is used for rotating the body portion of the mandrel relative to the extension 31 in the proper direction to tighten or tension the hair thereon. Rotation of the mandrel in the opposite direction will be precluded by the spring clutch 32. Rotation of the extension in either direction will be precluded when the latch 34 is in the slot 33 in said extension.

When it is desired to remove the mandrel from the clamping member, it is not necessary to first operate the clamping member to release the hair and thereby release the tension of the hair wound on the mandrel. It is merely necessary to swing the latch 34 out of the slot 33 which will permit bodily rotation of the mandrel together with the extension 31 and thereby release the tension on the hair. The mandrel may then be readily removed from the clamping member.

60 In Figure 6 I show slightly different locking mechanism for locking the arms 1 and 2 of the hair clamping member together. The structure is the same as that previously described with the exception that a keeper 26a is provided which engages the lug 25 on the latch member 22. This keeper 26a is pivoted as at 41a and is also pivotally connected to the inner end of a pin 42a. The keeper 26a is normally engaged in locking relation to the latch member 22 by a spring 27a. 65 However, the keeper 26a may be disengaged from the latch member 22 merely by pressing inwardly on the outer end of the pin 42a. With this structure it is possible to release the arms 1 and 2 from each other so that they will spread apart 70 without operating the worm and gear mechanism 75

through the medium of the knob 19. It is merely necessary to press inwardly on the pin 42a.

Figure 7 shows a slightly modified structure whereby the same results may be accomplished as with the structure of Figure 6. In this instance the lug 25 on the latch member 22 projects in the opposite direction and projects beneath a keeper 26b. This keeper 26b is mounted on the inner end of a pin 43. It is normally held in engagement with the latch member by a compression spring 44 which urges the pin 43 and the keeper 26b inwardly at all times. The keeper 26b is preferably square in cross section and slides through a square opening so that it will not rotate. Thus, it will always retain its 15 original position. In order to release the latch member to permit the two arm members to swing apart in this instance, it is merely necessary to pull out slightly on the pin 43.

It will be apparent from the above description 20 that I have provided a hair clamping member having many desirable characteristics. It is of such a nature that it will grip the hair firmly regardless of the thickness of the strand of hair inserted therein. There will be no danger of 25 slippage of the hair through the clamping member when the hair is being tightened on the mandrel and therefore there will be no pulls on the scalp. The clamping member is of such a nature that it will adequately protect the scalp 30 from heat and there will be no danger of steam or hot waving fluid passing therethrough. The device may be easily and quickly operated to grip the hair and since it can be locked by operating a knob member disposed adjacent the 35 pivoted ends of the clamping arms rather than at the opposite end, its application to the hair is simplified. Furthermore, it is of such a nature that there will be no danger of injury to the hair. The mandrel is mounted on this 40 clamping member in a very desirable manner and it may be removed from the clamping member after the hair has been wound and tightened thereon, without first removing the clamping member from the strand of hair. 45

Having thus described my invention, what I claim is:

1. A hair-clamping member comprising a plurality of arm members pivoted together for swinging movement relative to each other, means for locking said arm members together when they are moved into cooperative relation, said means comprising a wedge member carried by one of the arms and having an inclined surface, a latch member carried by one of the arms having a portion engaged by said surface and a portion which engages the other arm, and means for moving said wedge member and said latch member relative to each other so that said portion of the latch member which engages said inclined surface will move to various positions along said surface. 55

2. A hair-clamping member comprising a plurality of arm members pivoted together for swinging movement relative to each other, means for locking said arm members together when they are moved into cooperative relation, said means comprising a wedge member carried by one of the arms and having an inclined surface, a latch member carried by one of the arms having a portion engaged by said surface and a portion which engages the other arm, and means for moving said wedge member and said latch member relative to each other so that said portion of the latch member which engages said in- 70

clined surface will move to various positions along said surface, said means comprising screw and rack mechanism.

3. A hair-clamping member comprising a plurality of members movable apart to receive the hair and together to grip the hair, a wedge lock for locking said movable members together, and means for operating said wedge lock, said means comprising screw and rack mechanism.

10 4. A hair-clamping member comprising a plurality of members movable apart to receive the hair and together to grip the hair, a wedge lock for locking said movable members together and including a movable wedge member, means for moving said movable wedge member, said means comprising screw and rack mechanism.

15 5. A hair-clamping member comprising a plurality of members movable apart to receive the hair and together to grip the hair, a wedge lock for locking said movable members together, means for operating said wedge lock, and means other than said last-named means for releasing the lock.

20 6. A hair-clamping member comprising a plurality of members movable apart to receive the hair and together to grip the hair, a wedge lock for locking said movable members together, means for operating said wedge lock, said means comprising screw and rack mechanism, and means other than said screw and rack mechanism for releasing the lock.

25 7. A hair-clamping member comprising a plurality of arm members pivoted together for swinging movement relative to each other, means for locking said arm members together when they are moved into cooperative relation, said means comprising a wedge member and a latch member having a portion with which said wedge member engages and a portion engaging a co-30 operating portion on one of said arm members, and means for bodily moving said wedge member and latch member relative to each other.

40 8. A hair-clamping member comprising a plurality of arm members pivoted together for swinging movement relative to each other, means for locking said arm members together when they are moved into cooperative relation, said means comprising a wedge member carried by one of said arms and a member which engages the wedge member and which has a portion that engages the other arm, and means for moving one of said last-named members bodily relative to the other of said members.

45 9. A hair-clamping member comprising a plurality of arm members pivoted together for swinging movement relative to each other, means for locking said arm members together when they are moved into cooperative relation, said means comprising a wedge member carried by one of said arms and a member which engages the wedge member and which has a portion that engages the other arm, and means for moving one of said last-named members bodily relative to the other of said members, said means comprising screw and rack mechanism.

50 10. A hair-clamping member comprising a plurality of members movable apart to receive the hair and together to grip the hair, a wedge lock for locking said movable members together, means for operating said wedge lock, and means for automatically causing said members to move apart when the lock is released.

55 11. A hair-clamping member comprising a pair of arms pivoted together adjacent one end thereof, each arm comprising a housing, a resilient

member for normally maintaining said arm members apart, means for locking said arm members together when they are brought into cooperative relation, said means comprising a wedge member carried in the housing of one of said arms and movable longitudinally therein, said wedge having an inclined surface and a rack surface formed thereon, a screw engaging said rack surface and projecting from said housing for moving said wedge member longitudinally, said wedge member having a curled portion at the lower end of said inclined surface, a latch member having a portion engaged by said curled portion, said latch member projecting from said housing towards the other arm member and having a portion at its outer end adapted to engage a keeper member disposed on the other arm member, a spring with which the outer end of said latch member will engage for forcing it into engagement with the keeper, and a spring at the inner end of said latch member for normally urging the outer end thereof to move in one direction.

60 12. A hair-clamping member comprising a pair of arms pivoted together adjacent one end thereof, a resilient member for normally maintaining said arm members apart, means for locking said arm members together when they are brought into cooperative relation, said means comprising a wedge member carried by one of said arms and movable longitudinally thereof, said wedge member having an inclined surface and a rack surface formed thereon, a screw engaging said rack surface for moving said wedge member longitudinally, a latch member having a portion engaged by the inclined surface of said wedge member, said latch member projecting towards the other arm member and having a portion at its outer end adapted to engage a member disposed on the other arm member, means for engaging the outer end of said latch member to cause it to engage the member with which it cooperates, and a resilient member for normally maintaining said arm members apart when the locking mechanism is released.

65 13. A hair-clamping member comprising a pair of arm members pivoted together adjacent one end thereof, means for locking said arm members together when they are brought into cooperative relation, said means comprising a wedge member carried by one of said arm members and movable thereon, said wedge member having an inclined surface and a rack surface formed thereon, a screw engaging said rack surface for moving said wedge member, a latch member having a portion engaged by the inclined surface of said wedge member, said latch member projecting towards the other arm member and having a portion adapted to engage a cooperating portion on the other arm member, and means adapted to engage said latch member when the arms are swung together for causing the portion of the latch member to engage the cooperating portion on the other arm.

70 14. A hair-clamping member comprising a pair of arm members pivoted together adjacent one end thereof, means for locking said arm members together when they are brought into cooperative relation, said means comprising a wedge member carried by one of said arm members and movable thereon, said wedge member having an inclined surface and a rack surface formed thereon, a screw engaging said rack surface for moving said wedge member, a latch member having a portion engaged by the inclined surface of said wedge member, said latch member projecting

5 towards the other arm member and having a portion adapted to engage a cooperating portion on the other arm member, and means other than the screw member for causing said latch member to be disengaged from the cooperating portion on the other arm member.

15. Hair-waving apparatus comprising a hair-clamping member, said hair-clamping member comprising a plurality of members movable apart 10 to receive the hair and together to grip the hair, a wedge lock for locking said movable members together, a mandrel member, means for mounting said mandrel member on said clamping member in such a manner as to permit rotation thereof 15 in one direction but to preclude rotation thereof in an opposite direction, said means including a pivoted latch member carried by one of said last-named members which is engageable with or may be disengaged from a cooperating portion on the 20 other of said members.

16. Hair-waving apparatus comprising a hair-clamping member, said hair-clamping member comprising a plurality of members movable apart to receive the hair and together to grip the hair, 25 a wedge lock for locking said movable members together, means for operating said wedge lock, said means comprising worm and gear mechanism, a mandrel member, means for mounting said mandrel member on said clamping member 30 in such a manner as to permit rotation thereof in one direction but to preclude rotation thereof in an opposite direction, said means including a pivoted latch member carried by one of said last-named members which is engageable with or 35 may be disengaged from a cooperating portion on the other of said members.

17. Hair-waving apparatus comprising a hair-clamping member, said hair-clamping member comprising a plurality of members movable apart 40 to receive the hair and together to grip the hair, a wedge lock for locking said movable members together, means for operating said wedge lock, means other than said last-named means for releasing the lock, a mandrel member, means for 45 mounting said mandrel member on said clamping member in such a manner as to permit rotation thereof in one direction but to preclude rotation thereof in an opposite direction, said means including a pivoted latch member carried by one of said last-named members which is engageable with or 50 may be disengaged from a cooperating portion on the other of said members.

18. A hair-clamping member comprising a pair of hair-gripping members movable apart to remove the hair and together to grip the hair, means for locking said hair-gripping members together when they are brought into cooperative 5 relation, said means comprising a wedge member carried by one of said gripping members and movable thereon, said wedge member having an inclined surface and a rack surface formed thereon, a screw engaging said rack surface for moving 10 said wedge member and a latch member having a portion engaged by the inclined surface of said wedge member, said latch member projecting towards the other gripping member and having a portion adapted to engage a cooperating 15 portion on the other gripping member.

19. A hair-clamping member comprising a pair of hair-gripping members movable apart to remove the hair and together to grip the hair, means for locking said hair-gripping members 20 together when they are brought into cooperative relation, said means comprising a wedge member carried by one of said gripping members and movable thereon, said wedge member having an inclined surface formed thereon, means for moving 25 said wedge member on said gripping member, and a latch member having a portion engaged by the inclined surface of said wedge member, said latch member projecting towards the other gripping member and having a portion 30 adapted to engage a cooperating portion on the other gripping member.

20. A hair-clamping member comprising a pair of hair-gripping members movable apart to remove the hair and together to grip the hair, 35 means for locking said hair-gripping members together when they are brought into cooperative relation, said means comprising a wedge member carried by one of said gripping members and movable thereon, said wedge member having 40 an inclined surface formed thereon, means for moving said wedge member on said gripping member, a latch member having a portion engaged by the inclined surface of said wedge member, said latch member projecting towards the 45 other gripping member and having a portion adapted to engage a cooperating portion on the other gripping member, and means other than said means for moving the wedge member for causing said latch member to be disengaged from 50 the cooperating portion on the other gripping member.

PETER SANTURELLO.

CERTIFICATE OF CORRECTION.

Patent No. 2,034,635.

March 17, 1936.

PETER SANTURELLO.

It is hereby certified that error appears in the printed specification of the above numbered patent requiring correction as follows: Page 1, first column, line 43, strike out the words "more, the mandrel is preferably mounted in such" and insert instead the syllable and words "ries a mandrel which is mounted thereon in such; and that the said Letters Patent should be read with this correction therein that the same may conform to the record of the case in the Patent Office.

Signed and sealed this 5th day of May, A. D. 1936.

Leslie Frazer

Acting Commissioner of Patents.
